UNITED STATES PATENT OFFICE.

LYLE N. SNOW, OF QUINCY, ILLINOIS, ASSIGNOR TO H. M. SHEER COMPANY, OF QUINCY, ILLINOIS, A CORPORATION OF ILLINOIS.

OIL BURNER.

Application filed October 6, 1927. Serial No. 224,436.

This invention relates to an improvement in oil burners.

The invention relates to oil burners of the air-blast type, in which a curved air pipe 5 extends over the oil cup of the burner and delivers air from the sides thereof to this oil cup, discharging the air downwardly about the vapors delivered from the oil cup. The air pipe has the opposite ends thereof 10 communicating with air passages upward through the bowl of the oil burner, receiving the air therefrom and discharging it through a central outlet branch or opening located immediately above the oil cup. A flame deflector may be seated upon the oil cup for the purpose of aiding the vaporization of the oil and also preventing the air from passing directly into contact with the oil intake opening.

20 The object of this invention is to permit of easily swinging the air pipe to one side without necessitating its removal entirely in order to gain access to the flame deflector for cleaning it as well as the oil cup and 25 for facilitating the starting of the burner. The invention also has in mind improving the structure of the flame deflector by providing a plurality of prongs which extend down from a circular flange or collar into 30 the oil in the cup, thus aiding a vaporization of the oil by reason of the heat carried downward from the top of the flame deflector by the conduction of the prongs, insuring a quick saving of time required to heat the 35 oil cup to a point where it would vaporize the oil. The collar of the flame deflector covers the upper edge of the oil cup preventing the accumulation of soot thereon.

In the accompanying drawings:—

40 Fig. 1 is a sectional view through an oil burner embodying the invention;

Fig. 2 is a top plan view of the same;

Fig. 3 is a disassembled perspective view of the burner and its parts; and

45 Fig. 4 is a bottom perspective view of the flame deflector.

The numeral 1 indicates the bowl of the burner, which is provided with a peripheral flange 2, serving to support the burner on a 50 ring or other suitable supporting member which connects it with a stove or other furnace structure with which it is used. Extending upwardly through the bowl 1 are two diametrically opposite air-passages 3

and 4 formed integrally with the bowl. At 55 least, the air-passage 3 is preferably round in cross section. An air-pipe 5 has the opposite ends thereof turned downward to form induction branches 6 and 7. The air-passages 3 and 4 are preferably flush with 60 the top of the burner bowl, and the induction branches 6 and 7 are seated upon the upper ends of these air-passages, the branch 7 being flush with the upper edge of the air-passage 4. A tubular extension 8 is formed 65 on the lower end of the induction branch 6 but of a reduced external diameter, forming a shoulder 9 which is seated upon the upper end of the air-passage 3 while the extension 8 projects into this air-passage and has a 70 snug fit therein.

Lugs 10 extend downward from the extension 8 and form guides therefor within the air-passage 3. The air-passage 3 as well as the extension 8 being round or cylindrical, 75 as shown in Fig. 2, the air-pipe 5 is permitted to be turned into the dotted line position of Fig. 2, the bearing surface between the cylindrical extension 8 and the air-passage 3 serving as a pivot for the air-pipe 80 and permitting of its being turned.

An outlet branch or opening 11 is provided at the center of the air-pipe 5 for allowing the air to flow downwardly over the center of the bowl. Located in the bottom center 85 of the bowl is an oil cup 12 which is supplied with oil or a liquid hydrocarbon through a main supply pipe 13, leading into the bottom of the bowl, as shown in Fig. 1. This cup 12 rises above the bottom of the bowl 90 and is formed integral therewith. A circular peripheral trough 14 is also formed about the oil cup 12 in order to receive any oil that may overflow from the cup. A flame deflector designated generally by the numeral 15 is adapted to be seated upon the oil cup. This flame deflector is provided with a hood 16 and a collar 17 connected together by means of flared legs 18. Prongs 19 extend downward from the collar 17 and while 100 the collar is seated upon the upper edge of the oil cup 12, these prongs are adapted to extend into the oil cup to a point near the bottom thereof for guiding the proper seating of the flame deflector as well as to conduct the heat downward from the hood 16 into the oil cup for aiding the vaporization 105 of the oil. An eyelet 20 is formed on the

top of the hood 16 for receiving a hook which may be used to remove the flame deflector whenever desired.

In the operation of the burner, the draft 5 formed by the burning hydrocarbon causes a movement of the air as indicated by the arrows in Fig. 1. The heated and vaporized oil passes upward from the oil cup to a point where the combustion takes place as 10 the air is drawn downward through the opening 11 about the periphery of the flame deflector 15.

The prongs 19 which extend down into the oil in the oil cup cause a quick vaporization of the oil by the conducting of the heat downward from the hood 16, insuring a quick starting of the burner and avoiding the unnecessary length of time it would otherwise take to heat the oil cup and the 15 bowl to a point where they would vaporize the oil. Furthermore, soot or dirt has a natural tendency to form on the flame deflector and top edge of the oil cup, which is made integral with the burner bowl. The flame deflector being made removable permits of the cleaning of this soot as well as a quick starting of the burner. The collar 17 serves to shield the top edge of the oil cup so that the removal of the flame deflector also 20 moves all of the soot, leaving the top edge of the oil cup entirely clean. During the operation, the soot also has a natural tendency to accumulate on the supports for the hood and by making them flared outward 25 30 apart from each other, as shown in Fig. 1, it tends to prevent this accumulation of soot and requires a much greater time for it to close over the opening between the hood and the collar, preventing the escape of 35 40 the vaporized oil. In fact, this closing up of the flame deflector by the soot is almost rendered impossible by reason of the structure of the flame deflector.

The structure of the air-pipe also provides for an easy removal of the flame deflector to permit of the proper cleaning of the flame deflector as well as of the oil cup. The bearing formed between the induction branch 6 and the air-passage 3 permits of 45 50 55 60 65 70 75 80 85 90 95 100 105 110 115 120 125 130 swinging the air-pipe out of its position over the flame deflector to gain access to the oil cup and to remove the flame deflector without the necessity of removing the entire air-pipe. In fact, it is possible to swing the air-pipe to one side and remove the flame deflector, placing another in its place, and then return the oil-pipe to its proper and operative position without stopping the operation of the burner, or at least without 80 85 90 95 100 105 110 115 120 125 130 waiting for the entire structure to cool. In this way, an oil burner is provided of a very greatly improved structure, which facilitates a quick starting of the burner, and permits of an easy cleaning thereof, which is not obtained in the usual oil burner where it is

necessary to entirely remove the air-pipe before access may be gained to the oil cup.

I claim:

1. An oil burner including a bowl, an oil cup connected therewith, air-passages 70 formed in the bowl, and a pivotally mounted air-pipe cooperating and associated with the air-passages and adapted to swing into proper position over the oil cup.

2. An oil burner including a bowl and having an oil cup therein, air passages extending into the bowl, and an air pipe having an end thereof pivotally received in at least one of the air-passages forming a bearing for said air-pipe and extending into operative position over the oil cup and air-passages. 80

3. An oil burner including a burner bowl having an oil cup therein, air-passages extending through the bowl, a removable flame 85 deflector seated upon the oil cup, and an air pipe having the opposite ends thereof forming induction branches and having a discharge outlet intermediate said branches, said outlet being normally located in operative position above the flame deflector and oil cup, at least one of said induction branches being flush with one of the air-passages, and bearing means connected with the other induction branch and air passage 95 for forming a pivotal connection between the air-pipe and said air-passage to allow a swinging of the air-pipe away from its operative position above the flame deflector and oil cup. 100

4. An oil burner including a burner bowl having an oil cup therein, a removable flame deflector seated upon the oil cup, air-passages extending upward through the burner bowl and being approximately flush with the upper surface thereof, an air pipe having the opposite ends thereof turned downward to form induction branches, and provided with an intermediate outlet normally positioned above the flame deflector and oil cup, one of said induction branches being approximately flush with and adapted to cooperate with one of the air-passages, the other induction branch having a reduced cylindrical extension formed thereon providing a shoulder seated upon the upper edge of the other air-passage, said extension projecting into the air passage and forming a pivotal bearing for the air pipe, to permit of a swinging of it away from its position over the flame deflector and oil cup, and guide lugs extending downward from the cylindrical extension. 115

5. A flame deflector for an oil cup said deflector having a hood, a collar adapted to be seated upon the edge of the oil cup, and legs connecting the collar with the hood. 125

6. A flame deflector for an oil cup said deflector having a hood, a collar adapted to be seated upon the edge of the oil cup, legs 130

connecting the collar with the hood, and prongs extending downward from the collar adapted to fit into the oil cup.

7. A flame deflector for an oil cup said deflector having a hood, a collar adapted to be seated upon the rim of the oil cup, flared legs connecting the collar and hood together and holding them in spaced relation, and a plurality of prongs extending downward from the collar adapted to fit into the oil cup.

8. An oil burner including a bowl having an oil cup therein, air passages associated with said oil cup, and an air pipe having the ends thereof cooperating with the air passages and having an intermediate opening above the oil cup, at least one of the ends of said air pipe being pivotally mounted for swinging movement.

9. An oil burner including a bowl having an oil cup therein, air passages associated with said oil cup, a removable flame deflector seated upon the oil cup, an air pipe having the ends thereof cooperating with the air passages and having an intermediate opening above the oil cup, and bearing means for pivotally supporting said air pipe at an end thereof.

10. An oil burner including an oil cup, air passages associated with said oil cup, and arranged on different sides thereof, and an air chamber having openings cooperating with the air passages and oil cup, said air chamber being pivotally mounted for swinging movement.

In testimony whereof I affix my signature.

LYLE N. SNOW.
